By R. F. Hyde Atty.

UNITED STATES PATENT OFFICE.

JOHN MURPHY, OF SPRINGFIELD, MASSACHUSETTS.

RING-EXTRACTOR FOR CARTRIDGES.

SPECIFICATION forming part of Letters Patent No. 291,619, dated January 8, 1884.

Application filed November 19, 1883. (No model.)

To all whom it may concern:

Be it known that I, JOHN MURPHY, a citizen of the United States, residing at Springfield, in the county of Hampden and State of Massachusetts, have invented an Improvement in Ring-Extractors, of which the following is a specification.

This invention consists of a ring or hand cartridge-extractor having three hooks, two of them, rigidly connected, being opposite each other and separated by an interval representing the diameter of the head of the "shell," and the third hook arranged upon the end of an arm hinged between the rigid hooks, so that it is adapted to be swung into a position to be slid with the other two over the rim of a cartridge, and form in effect the ordinary three-hook hand-extractor now in general use; but when the extractor is not required for use, the movable hook is adapted to be folded to leave a flat implement, as would in effect be formed by the ordinary extractor were its third hook cut off flush with the ring-handle and opposite hooks, and a tool consequently which can be transported comfortably in any pocket upon the person. This is fully illustrated in the accompanying drawings, in which two ways of hinging the movable hook are shown, and in which drawings—

Figure I is a plan view of an open extractor having the movable hook to swing in the plane of the rigid ones. Fig. II is a side elevation of the same; and Fig. III is a plan view of the same with the movable hook folded. Fig. IV is a plan view of an open extractor, having the movable hook to swing in a plane at right angles to that occupied by the other hooks. Fig. V is a plan view of the same with the movable hook folded. Fig. VI is a side elevation with the movable hook extended. Fig. VII is the same with the movable hook folded; and Fig. VIII is an edge elevation of the extractor with the swinging hook extended.

In Figs. I, II, and III, B is the swinging hook, hinged at b between the rigid hooks C D, and at a point nearer the one D, to permit the hook when swung out to come upon the

perimeter of a circle resting within the ones C D. The face of the extractor is cut away between the hooks C D to the depth of the swinging hook-arm, to leave a shoulder, d, which forms a stop to the hook B when swung out, as seen in Fig. I, or when swung out upon the opposite side.

The face of the hook-arm of B, and of the extractor where not cut away, being flush, forms a flat surface, as in the face of the ordinary extractor, to guide all of the hooks to their place upon the rim of the cartridge. The hook B from a folded position can be swung out to either side by a finger of the hand grasping the extractor, and when closed, as shown in Fig. III, the extractor from its flat shape takes up but little room, and can be carried conveniently in a vest-pocket.

Without a departure from the spirit of my invention, the hook B may be upon the end of an arm, B', hinged at b upon an axis parallel to the face between the hooks C D, to swing in a plane at right angles to that in which are the hooks C D, and to be extended for use, as shown in Figs. IV, VI, and VIII, or folded out of the way, as seen in Figs. V and VII.

As a convenient way of combining the swinging hook B with the body of the extractor, a recess, e, is cut entirely through the extractor at the top of the ring. This recess is of the width of the hook-arm B'. Through the recess e, from edge to edge of the extractor, and parallel to each other, extend the pins g h. The one g forms a hinge-pin to the hook-arm B', and the one h a stop, against which the arm B' brings up when thrown open, to assure the hook B being in the same plane with the hooks C D. The arm B' is cut away at f to pass over the pin h, to permit the other side of the arm to lie flush with the side of the extractor when folded.

In operation, the arm B' with its hook is, from the position shown in Fig. VII, swung over, as indicated in dotted lines, Fig. VIII, to be stopped in a position to render the extractor available for use.

Now, having described my invention, what I claim is—

The within-described cartridge-extractor, consisting of a convenient handle, two opposite rigidly-connected hooks, and a third hook hinged between the rigid ones, and 5 adapted to swing between them from an operative position to a folded one, to leave an implement of no greater thickness approxi-

mately than the width of the face between the rigid hooks, as and for the purpose set forth.

JOHN MURPHY.
